UNITED STATES PATENT OFFICE.

JOHN H. HERMANN, OF HIGHLAND, ILLINOIS.

COMBINED CAN ROSINING AND SOLDERING MACHINE.

SPECIFICATION forming part of Letters Patent No. 339,774, dated April 13, 1886.

Application filed January 5, 1886. Serial No. 187,744. (No model.)

To all whom it may concern:

Be it known that I, JOHN H. HERMANN, a citizen of the United States, residing at Highland, in the county of Madison and State of Illinois, have invented certain new and useful Improvements in Combined Can Rosining and Soldering Machines, of which the following is a specification.

My invention specially relates to that class of machines for soldering the end seams of sheet-metal cans in which the cans are inserted in a holder which is supported by a standard, so as to rotate while holding a can, and is universally adjustable, so as to rotate in any angle required, for the purpose of first rotating the can in a flux or rosin box and then in a box or pot of molten solder.

The construction and operation of the machine will first be described, and then those parts and combinations which constitute my invention will be designated in the claims.

In the drawings hereto annexed, Figure 1 is a front elevation of the machine, clearly showing a can held by the holder in position ready for being soldered, and also showing a gaso-line-burner under the solder-box, the rosin-box being shown, partly by full and partly by dotted lines, behind the solder-box. Fig. 2 is a top plan view of the machine, showing the can held by the holder in position ready for being rosined. Fig. 3 is a top plan view of Fig. 1. Fig. 4 is a detail section of the rosin-box, showing the manner of adjusting it in position for the holder, a can being shown in position for being rosined. Fig. 5 is a detail section through the solder-box, showing its adjustable features with a can in position. Fig. 6 is a detail view of the soldering-iron with a can in position. Fig. 7 is a plan section through the soldering-iron and can on line 7 7 of Fig. 6. Fig. 8 is a front view of the disk at the end of the can-holder shaft, showing the clutch device. Fig. 9 is a section on line 9 9 of Fig. 8. Fig. 10 is a rear view of Fig. 8 on line 10 10 of Fig. 1.

A is the frame of the machine, and *a* are its four legs or standards, all made of iron. Within the frame is placed and securely fastened a wooden bed or top, B.

C is an iron pot or box which holds the hot solder. This box is preferably placed at the left front corner of the frame A, and is bolted

or otherwise held in the same. When the solder-box is in position, as shown in the drawings, its ends and sides at the top are flush with the top of the wooden bed B.

D is the rosin-box. This is placed preferably at the rear left corner and top of the bed B.

E is my improved adjustable rotating can-holder, which is supported on a post, E', placed to the right of the solder-box and in line with the center of same, as shown in Figs. 2 and 3.

I will first proceed to describe my improved adjustable and rotating can-holder, then the rosin-box, its adjustable features, &c., and its relation to the can-holder, and, finally, the solder-box and its adjustable soldering-iron and its relation to the can-holder.

The post E' is made hollow and is fastened to the top of the wooden bed at its flange *e* by means of screws, nails, or bolts. Within this hollow post E' is placed the shank end of a forked rod, E², which is fitted so that the fork E³ will turn in the hollow post.

The holder E has on its shaft a loose collar or sleeve, *e'*, by which it is pivoted or hinged in the fork E³, as shown in Fig. 1. The holder thus rotates in the sleeve, which serves as a bearing, as well as permitting the holder to slide up and down in it, as indicated by dotted lines in Fig. 1, for the purpose of adapting it to long and short cans, as will hereinafter be fully described.

F is a crank or hand wheel keyed to the upper end of the holder-shaft, and by which the holder is turned or rotated.

*e*² and *e*³ are collars or rims on the shaft, which limit the sliding movement of the holder in the collar or sleeve. The fork E³, in which the collar or sleeve is pivoted, permits the lower or long arm of the holder to be raised and lowered as a lever-arm, and the object of allowing the fork to turn in the hollow post is to permit the holder to swing around horizontally to any point of the circle around the post as its center for various purposes, as will be described farther on. To the lower end of the holder opposite to the hand-wheel F is provided my improved clutch device, which is constructed as follows:

G is a disk or circular plate, riveted or otherwise secured at its center to the lower end of the holder-shaft. Through this disk are cut or cast two slots, *g* and *g'*, directly opposite

each other, running radially, beginning near the center of the disk and extending toward its periphery. Within these slots g and g' are placed my two clutch-pieces, H and H' , respectively, which form my adjustable clutch device for gripping cans of different diameters. One of the clutch-pieces, H , is first adjusted on the face of the disk to the size of the can to be clutched, and is held firmly and rigidly in the required position by means of a bolt, h , which passes through the slot g , and a nut, h' , of the bolt at the other side of the disk. The opposite clutch-piece, H' , is made movable on the disk and in its slot g' , and is firmly held to a plate, h^2 , upon which it is adjusted to the size of the can by a bolt, h^3 , which passes through the slot g' of the disk, and a slot, h^4 , of the plate h^2 , and a nut, h^5 , of the bolt h^3 at the back. This plate h^2 is placed at the back of the disk over the slot g' , so that its slot h^4 is in line with and parallel to the slot g' of the disk.

To the end of the plate h^2 nearest the center of the disk is provided a lug, h^6 , which extends into the slot of the disk, and moves in same, for guiding the movement of the plate, &c. Into this lug h^6 , which is hollow, is inserted the short arm of a spring-lever, I , which is fulcrumed in a lug, i , cast on the holder-shaft, the other or long end of which lever I is provided with a spring, i' , riveted on its inner side and acting against the holder-shaft, as clearly shown in Figs. 1 and 3.

To allow the clutch-piece H' to move freely in the slot g' of the disk after it is firmly adjusted to the back plate, h^2 , I provide it with a lug, h^7 , which fits the slot g' , and passes through it and acts as a shoulder, against which the plate is bolted, the bolt itself passing through this guide-lug. The spring i' keeps the long arm of the lever I out, and the short arm in which latter keeps the plate h^2 and its clutch-piece H' in toward the center of the disk for clamping and holding the can.

The two clutch-pieces H and H' are each provided with a pair of arms, k , which are made adjustable on the same by means of the same bolt and nuts which secure each to the respective disk and plate, and which pass through their hub k' . (See Figs. 8, 9, and 10.) When the spring-lever I is pressed with the long arm against the holder-shaft by the operator, who grasps his hand around both the shaft and the lever, the short arm draws the plate with the clutch-piece H' away from the opposite stationary clutch-piece, H , or, in other words, the clutch device is opened to receive a can or to release one.

The rosin-box D is placed as shown in Figs. 2 and 3, and is hinged in an upright frame, D' , which is adjustable to the right and left, so as to bring the rosin-box farther to the right or left on the wooden frame B by a bolt, d , which passes through the cross-piece of the frame D' and slot d' , cut in the wooden bed, and a nut, d^2 , below, as clearly shown in Fig. 4. The frame D' also turns on the said bolt,

so as to bring the rosin-box in line with the hollow post on which the can-holder turns and swings.

The rosin-box is preferably made of the shape shown in Fig. 1, its upper end being open for receiving the rosin, and a segmental circular opening at the front near the bottom directly above my improved rosin-distributer D^2 , which latter I make of leather, rubber, or other yielding material, and of a segmental shape reverse to the segmental opening d' , so that a can held in the holder will rest with its edge and bottom in same as its bearing in D^2 which it rotates when the holder is turned.

D^3 is a scoop forming part of the box below for guiding the can into the position for being rosined, as well as for receiving the rosin which may drop out of the box through the opening d' over the rosin-distributer. The rosin box being hinged in the frame D' , as described and shown in Fig. 4, is thus permitted to tilt into any position or angle required to bring the front face flush against the bottom of the can. The can while rotating in the rosin-distributer causes the rosin from the segmental opening to drop between it and the distributer, which latter distributes the rosin evenly around the edges of the can and bottom while the can rotates.

The rosin-distributer may be made semi-circular instead of segmental, if desired to encircle more of the can, and is cut from heavy sheet-rubber or leather, preferably. The rosin-box itself is made of wood, and its front face is covered with sheet or plate steel d^4 , (see Fig. 4,) for the purpose of preventing the edges of the cans from cutting into the wood. An opening, b , is cut in the wooden bed B , for the solder-box C . This opening, as shown in Figs. 2 and 3, should be sufficiently large to leave space enough between it and the solder-box to prevent the wooden bed from catching fire from the burner C' under the box. The burner C' serves to melt the solder in the solder-box, and may be a gasoline, gas, or other burner.

There are lugs cast at the top of the two sides of the solder-box, and within these lugs is hinged a frame, C^2 , to which is secured my improved soldering-iron C , which is of the shape clearly shown in Fig. 2. The hinged frame C^2 is of the $\square$ shape, the two arms of which serve as guides and supports for the soldering-iron, also clearly seen in the same figure. The lower end of the soldering-iron is provided with two segmental lugs or solder-spreaders, c and c' , which receive the end of the can and bottom (see Fig. 6) and partly encircle the same on each side, leaving part of same free below, so as to dip into the solder, which latter should about touch the segmental spreaders c and c' , as clearly shown in Fig. 5. These segmental solder-spreaders have their spreading-edge c' beveled inwardly to correspond to the outward bevel c , formed at the joint between the bottom of the can and the end of the can itself, so that a can when in position

between the spreaders is held as shown in Figs. 6 and 7, the beveled edge of the can-bottom extending in behind the front face of the segments, as clearly shown by dotted lines in Fig. 6, the outer edge of said spreaders serving to scrape the can clean from all solder adhering to its sides by coming flush against the sides of the can itself. (See Fig. 7.) Further, the soldering-iron C³ is provided with a 10 semicircular or segmental notch, f, at the bottom between the two solder-spreader, the edge of which said notch f serving to scrape the surplus solder from the bottom of the can as it rotates.

15 The rosin-spreader of the rosin-box should have its spreading-edge similarly shaped as the spreading-edge of the solder-spreader just described, for the purpose of removing the surplus rosin from the side of the can. 20 The segmental or semicircular opening in the front of the rosin-box, directly above the rosin distributor or spreader, removes the surplus rosin from the bottom of the can as it rotates.

In order to make the soldering-iron with its 25 spreaders adjustable to the height or amount of solder within the box, and so that the edge of the can will dip into the hot solder, as shown in Fig. 5, a rod, c⁵, is secured to the upper end of the plate or soldering-iron C³ by 30 riveting or otherwise. The opposite or upper end of the rod c⁵ passes through a hole in the upper cross-piece of the hinged frame C², and a thumb-nut, c⁶, at the top screws on the threaded end of said rod, and holds same 35 with the soldering-iron as required. By turning the thumb-nut to the right or left the soldering-iron is raised or lowered. The hinged frame C² permits the soldering-iron to tilt to the angle required for receiving the 40 end of the can when held in the holder, so that the bottom of the can will rest flush against the face of the soldering-iron, and the segmental solder-spreader will properly engage the edge to be soldered, as shown in 45 Figs. 2, 5, 6, and 7.

When a change is made from one size of cans to another, it is necessary to change the soldering-iron for a larger or smaller one to correspond by removing the thumb-nut at the 50 end of the rod c⁵.

The difference in the soldering-irons for different-sized cans will only exist in the solder-spreader, which will be of different radii at the spreading-edges c³, the soldering-irons C³ proper being of uniform size and shape, so as to fit the hinged frame C² alike. A change, however, of the rosin-box is not always necessary, unless the size of cans to be received by it are too large to be admitted within the 55 rosin-distributer, which will serve its purpose for several different sizes of cans.

The clutch device of the rotating can-holder will adapt itself to several different sized cans and is but required to be adjusted by setting 60 the clutch-pieces H and H' nearer together or farther apart, as before described.

The soldering-iron C³ and its solder-spreader

ers may be made of tempered steel, so as to better withstand the constant wear to which they are subjected when many cans are soldered.

Having now fully described the construction of my newly-invented can rosining and soldering machine, the operation of same is as follows: The clutch device of the rotating can-holder is first adjusted to the diameter of the cans to be rosined and soldered. The holder is now placed in position with its forked shank inserted into the hollow post. The holder E being universally adjustable in 80 any position, as already described, is brought with its clutch device around for receiving a can. The operator pressing the long arm of the spring-lever I toward the holder-shaft opens the clutch device and inserts a can, 85 which is immediately gripped firmly between the arms k of the two clutch-pieces upon releasing the spring-lever I. The rosin-box is now adjusted with its frame D', by means of the bolt d and nut d', within the slot d' of the 90 bed B and the frame turned on the bolt d, so as to bring the rosin-box in line with the hollow post and at the proper distance to properly receive the can when held by the holder E, as shown in Figs. 2 and 4. The soldering- 95 iron is next adjusted on the frame C² to the level of the hot solder contained in the solder pot or box, and so as to properly receive a can between its two segmental solder-spreader, c' and c², and so that the lower edge of the can 100 will dip into the hot solder, as clearly shown in Figs. 1, 3, and 5. The hinged frame C² is set so that the can when held by the holder-shaft E into the hot solder, as just described, will come with its bottom flush against the 105 soldering-iron C³, as shown in same figures.

The rosin-box now being supplied with powdered rosin, the operator takes hold of the can-holder shaft E with his left hand and the hand-wheel F with his right hand, swings 110 the holder around in line with the rosin-box and lowers it with the can into the rosin-box until the can rests within the rosin-distributer, the hinged box adjusting itself automatically with its front face flush against 115 the bottom of the can, through the weight of the can-holder overbalancing the box at the front and tilting it forward. A few turns are now given to the can by turning the hand-wheel F, and the rosin is distributed around 120 the joint, the surplus rosin removed from the can and bottom, as before described, and the can is ready for the soldering process. The operator now lifts the holder with the can up out of the rosin-box, brings it around and forward in line with the solder pot or box and lowers it down with the can, so that the latter fits and rests between the two solder 125 distributors or spreaders c' and c², as shown in Figs. 1, 3, 5, and 6, and the bottom of the can is flush against the soldering-iron C³. A few turns given the can again by the hand-wheel F, the solder is taken up by the end of the can 130 as it dips into it and is distributed around the

joint evenly by the solder-spreaders and the surplus rosin removed from the can and its bottom, thus finishing the can, ready for removal. The holder is again raised with the can, the clutch is opened to release the can, which is now removed and another can placed in its stead between the clutch-pieces, and the operation is repeated.

What I claim is—

- 10 1. The combination and arrangement, with a universally-adjustable rotating can-holder, of a rosin-box and solder pot or box, the rosin-box being adjustable within a frame, so as to receive the can when held by the rotating holder, and the solder pot or box having an adjustable soldering-iron within a hinged frame for receiving the can of the holder, substantially as herein shown and described, and for their respective purposes set forth.
- 15 2. The combination, with a can-holder-shaft, E, of the slotted disk G, clutch device H H', and spring-lever I, substantially as and for the purpose set forth.
- 20 3. In a can-holder, the combination of the disk G, provided with slots g and g', clutch-pieces H and H', slotted plate h², the respective bolts h and h³, nuts h' and h³, arms k, lug h⁶ of the plate h², spring-lever I, fulcrumed at i, spring i', and the holder-shaft E, substantially as herein shown and described, to form an improved adjustable spring-clutch device, for the purpose set forth.
- 25 4. The combination, with a can-holder shaft, E, of the slotted disk G, clutch device H H', spring-lever I, collars e² e³, loose sleeve e', and fork E³, supported on a bed, B, substantially
- 30 as shown and described, and for the purpose set forth.
- 35 5. The rosin-box D, provided with the scoop end D³, as herein shown and described, 40 and for the purpose set forth.
- 40 6. In a rosin-box, D, the combination, with a rosin-distributer, D', of the shape shewn and described, of the opening d⁴ in the face of the rosin-box, as and for the purpose set forth. 45
- 45 7. The rosin-box D, hinged within the adjustable frame D', as herein shown and described, and for the purpose set forth.
- 50 8. The combination, with a rosin-box, D, of the frame D', slot d' in the bed B, bolt d, and nut d', substantially as and for the purpose set forth.
- 55 9. The soldering-iron C⁶, made adjustable on the hinged frame C⁷ of the solder-box C by means of the rod c⁵ and nut c⁶, substantially as herein shown and described, and for the purpose set forth.
- 60 10. The combination, in a soldering-iron, C⁸, of the solder-spreaders c¹ and c², having bevelled segmental edges c³, with the soldering-iron C⁸ proper, having the notch f, substantially as and for the purpose set forth.
- 65 11. The combination and arrangement of the frame A, bed B, opening b, solder pot or box C, slot d', rosin-box D, and a universally-adjustable rotating can-holder, E, substantially as herein shown and described, and for the purpose set forth.

JOHN H. HERMANN.
